ROCKER SPRING FOR PLATFORM ROCKER

Martin Fox, Chicago, Ill., assignor to The Seng Company, a corporation of Illinois

Application July 24, 1957, Serial No. 673,911

1 Claim. (Cl. 155—71)

This invention relates to an improved rocker spring for platform rocking chair constructions.

The principal object of the present invention is to provide a rocker spring assembly for a platform rocking chair which reduces the overall height of a platform rocking chair.

A further object of the invention is to provide a rocker spring which is very strong, and which may be very easily secured to the base member and rocker member of a platform rocking chair.

Yet another object of the invention is to provide a rocker spring assembly having a bottom plate which lies flat upon the platform base, and has a downturned strengthening skirt around substantially its entire margin.

The invention is illustrated in a preferred embodiment in the accompanying drawings in which:

Fig. 1 is a fragmentary sectional view of a rotating platform rocking chair equipped with the rocker spring assembly of the present invention;

Fig. 2 is a fragmentary section on an enlarged scale taken substantially as illustrated along the line 2—2 of Fig. 1;

Fig. 3 is a plan view of the rocker spring;

Fig. 4 is a section taken substantially as indicated along the line 4—4 of Fig. 2;

Fig. 5 is a section taken substantially as indicated along the line 5—5 of Fig. 4;

Fig. 6 is a fragmentary section taken substantially as indicated along the line 6—6 of Fig. 5.

Referring to the drawings in greater detail, and referring first to Fig. 1, a rotary platform rocker is provided with a plurality of legs 10 surmounted by a turntable mechanism 11 on top of which is a rocking chair base frame 12 which is provided along its side margins with rocker rails 13.

Supported on rocker rails 13 are rocker members 14 which are flanked by side frame members 15 of the rocking chair structure. Interconnecting the base frame 12 and rocker members 14 are rocker spring assemblies 16 which embody the herein disclosed invention.

As best seen in Figs. 2 to 6, the rocker spring assemblies 16 have bottom plates 17 which are long, parallel sided members with rounded end portions and downturned supporting and strengthening skirts 18 each of which extends around the entire perimeter of the base member 17 and is provided in its forward margin with spring receiving slots 19. Thus, the skirt 18 defines an open bottom chamber 17a beneath the plate 17. To the rear of the spring receiving slots 19 are two pairs of radially extended downwardly struck bosses 20 which extend into the chamber 17a, and between each pair is a downwardly struck spring retaining hook 21, so that the lowermost convolutions of a pair of coil springs 22 may extend through the slots 19 and into chamber 17a where they are engaged by the lugs 20 and hooks 21 which act as spring retaining means. At the two ends

2

of the bottom plate 17 are apertures 23 (see Fig. 5) to receive fastening bolts 24 which extend upwardly through the rocker base 12 and are secured by nuts 25. Adjacent each aperture 23 is an upturned ear 26 which abuts a side of a nut 25 to prevent the nut from turning when the bolt 24 is being screwed in or out.

Mounted on top of the springs 22 is a top plate indicated generally at 27, which includes a plate body 28 substantially parallel to the bottom plate 17, an upstanding flange 29 at the front of plate 28, and an upstanding attaching flange 30 at the rear of plate 28 which is provided with suitable openings to receive wood screws 31 by means of which the upper spring plate is secured to the face 14a of rocker member 14. The top plate 27 is strengthened not only by the upturned flange and the attaching flange 30, but also by downturned end portions 32 and upwardly struck strengthening bosses 33 and 34 which extend from the attaching flange 30 forwardly to flank the rear portions of the springs 22.

20 Slots 35 in the front flange 29 receive the upper convolutions of the springs 22, and upwardly struck bosses 36 cooperate with upwardly struck hooks 37 to retain the springs in engagement with the top plate 27.

Reference to Fig. 1 shows that the present construction with its flat bottom plate to receive bolts which extend upwardly through the rocker spring base permits the use of a considerably lower rocker supporting rail 13 than is possible with a conventional rocker spring in which the bottom plate has a downturned attaching flange 30 like the flange 30 of the top plate. The assembly is also stronger and easier to mount, since the attaching bolts and nuts are alongside the springs instead of being beneath them as was necessarily true when the bottom plate had a downturned attaching flange which was the counterpart of the upturned flange 30.

Furthermore, the use of upturned ears 26 simplifies the fastening of the bottom plates to the rocker base frame.

The foregoing detailed description is given for clearness of understanding only, and no unnecessary limitations are to be understood therefrom, as some modifications will be obvious to those skilled in the art.

I claim:

45 A rocker spring assembly for platform rocking chairs comprising: a bottom plate having a downturned skirt extending substantially around its perimeter, said skirt defining an open bottom chamber, there being spring receiving slot means in a margin of said skirt and apertures adjacent opposite ends of the plate to receive attaching means for securing the bottom plate to a rocker base; a pair of coil compression springs mounted in upright position on said bottom plate with their bottom convolutions beneath the plate and extending through said slot means so they are partly in the chamber and partly outside it, said springs being between said apertures; integral means on the bottom plate to secure said springs thereto; a top plate with an upturned skirt having slot means in which the top convolutions of said springs are seated, a portion of said top plate being provided 50 with apertures to receive fastening means for securing it to a rocker member; and integral means on the top plate to secure it to said springs.
